(57) **CLAIM**

The ornamental design for a portion of a control panel housing, as shown and described.

DESCRIPTION

FIG. 1 is a top perspective view of a portion of a control panel housing showing our new design;

FIG. 2 is a right side elevational view of the portion of the control panel housing of FIG. 1, the left side elevational view of the portion of the control panel housing being a mirror image thereof;

FIG. 3 is a front elevational view of the portion of the control panel housing of FIG. 1;

FIG. 4 is a rear elevational view of the portion of the control panel housing of FIG. 1; and,

FIG. 5 is a top plan view of the portion of the control panel housing of FIG. 1.

The broken lines having consistent dash lengths (dash-dash-dash) are shown on the control panel housing for illustrative purposes only and form no part of the claimed design.

The broken lines having variable dash lengths (long dash-short dash-long dash) are boundary lines representing a boundary of the claimed design.

1 Claim, 5 Drawing Sheets
